US00D834044S

(12) **United States Design Patent** (10) Patent No.: **US D834,044 S**
Everhart et al. (45) Date of Patent: **** Nov. 20, 2018**

(54) **DISPLAY SCREEN WITH GRAPHICAL USER INTERFACE FOR A LABORATORY INSTRUMENT**

(71) Applicant: **Beckman Coulter, Inc.**, Brea, CA (US)

(72) Inventors: **Nicholas Everhart**, Minneapolis, MN (US); **Dana Vajen Habig**, Cincinnati, OH (US); **Shaohui Qiu**, Belmont, MA (US); **Andrew Cottrell**, Minneapolis, MN (US); **Daniel Sunoh Choe**, Minneapolis, MN (US)

(73) Assignee: **Beckman Coulter, Inc.**, Brea, CA (US)

(**) Term: **15 Years**

(21) Appl. No.: **29/572,369**

(22) Filed: **Jul. 27, 2016**

(51) LOC (11) Cl. **14-04**

(52) U.S. Cl. **14/486**

(57) **CLAIM**

The ornamental design for the display screen with graphical user interface for a laboratory instrument, as shown and described.

DESCRIPTION

FIG. 1 is a front view of a first embodiment of the display screen with graphical user interface for a laboratory instrument; and,

FIG. 2 is a front view of a second embodiment thereof. The broken lines in the Figures are for illustrative purposes only and form no part of the claimed design. The broken line perimeter in the Figures is included for the purpose of showing a display screen and forms no part of the claimed design.

1 Claim, 2 Drawing Sheets
